REFRIGERATING APPARATUS

Lawrence A. Philipp, Detroit, Mich., assignor to
 Kelvinator Corporation, Detroit, Mich., a corporation of Michigan

Application May 3, 1932, Serial No. 608,941

11 Claims. (Cl. 62—116)

This invention relates generally to refrigerating apparatus and more particularly to refrigerating apparatus of the household type.

Heretofore it has been customary when installing refrigerating apparatus on or in refrigerating cabinets to mount the refrigerant low side such as the cooling coils or chamber within the food compartment or in a cooling chamber of the cabinet and to mount the refrigerant high side such as the compressor and condenser either above the top wall or below the bottom wall of the food compartment. Ordinarily it was difficult to install the machine in the cabinet or to remove it therefrom under these conditions. Frequently the space occupied was great since it was necessary to allow not only the actual space required by the cabinet and machine, but also sufficient space for installing or removing the machine. In addition, such installations usually included box-like covers or cages for the machine, and such enclosures were unsightly. When placed at the bottom of the cabinet the machine occupied space which might otherwise have been useful for cupboard space or for receiving foods and from an efficiency standpoint was objectionable. Due to the location and arrangement of parts, the entire machine could not be installed in or removed from the cabinet without making or breaking pipe connections, with the consequent chances of gas and oil escaping or dirt and moisture entering the system. This required skilled workmen. In fact such workmen had to leave the service station or factory to travel to and from installations and thereby consumed much time in just traveling as truck drivers back and forth between jobs. Consequently such workmen were unable to devote their entire time to skilled work and were expensive to maintain.

With the present invention, however, the high and low sides are arranged side by side in a common horizontal plane and may be readily installed within or removed from a cabinet adjacent the top thereof without uncoupling or breaking any refrigerant connections or disassembling any of the parts so that (a) refrigerant and/or oil cannot escape from the apparatus during installation or removal; (b) unskilled labor such as ordinary truck drivers may be used to make such installations or removals; and (c) skilled labor may remain in a central service station and devote its entire time to skilled service work.

Accordingly, one of the objects of my invention consists in a new and improved arrangement of a refrigerating system within a refrigerator cabinet.

Another object of the invention is to provide a refrigerator cabinet with a refrigerating system and to arrange for the ready removal of the system as a unitary structure from the cabinet in a new and improved manner.

Another object of the invention is to provide a refrigerator cabinet with a food storage compartment and a machinery compartment and to provide a refrigerant cooling element in the food compartment and a refrigerant condensing element in the machinery compartment and to arrange for the ready removal of said elements and machinery compartment as a unitary structure from the cabinet whereby the necessity of uncoupling the elements or removal of the cabinet panels and the like is avoided.

Further objects and advantages of the present invention will be apparent from the following description, reference being had to the accompanying drawings, wherein a preferred form of the present invention is clearly shown.

In the drawings:

Fig. 1 is a vertical view in cross section of a refrigerator embodying features of my invention;

Fig. 2 is a vertical sectional view taken in the direction of the arrows 2—2 of Fig. 1;

Fig. 3 is a top view in cross section, taken along the line 3—3 of Fig. 1 showing the arrangement of the refrigerating system within the cabinet;

Fig. 4 is a side view in elevation of the refrigerating system removed from the cabinet;

Fig. 5 is a vertical sectional view of a modified form of refrigerating apparatus embodying features of my invention;

Fig. 6 is a vertical sectional view taken in the direction of the arrows 6—6 of Fig. 5;

Fig. 7 is a top view in cross section taken along the line 7—7 of Fig. 5; and

Fig. 8 is a view in elevation of the refrigerating system and machinery compartment removed from the cabinet.

Referring to the drawings and particularly to Figs. 1, 2, 3 and 4, numeral 20 indicates in general a cabinet having a metallic lining member 21 formed to provide the inner walls of a food storage compartment 23 and preferably having a coating of vitreous enamel such as porcelain. The cabinet includes insulated walls including top wall 24, rear wall 25, side walls 26, bottom wall 27 and front wall 28. An outer metallic casing 29 is provided for enclosing the insulated walls. The front wall 28 is provided with an opening 30 through which access to the compartment 23 may be had, and a movable closure member or door 31 to close the opening. The

edges of the door opening are provided with finishing strips 22 which cover the edges of the inner lining 21 and the outer casing to provide a neat appearing finish. An opening 32 is provided in the rear wall 25 of the cabinet.

A removable unitary structure is arranged within the confines of the inner lining member 21 near the top of the food storage compartment 23 and includes a refrigerant cooling element 35, an insulated machinery compartment 36, and a refrigerant condensing element. The machinery compartment is formed by a wall structure of some suitable insulating material such as cork board and is provided with an opening 37 which registers with the opening 32 in the rear wall 25. The machinery compartment includes an upright wall 42, side walls 43 and a bottom wall 44. The upright wall 42 extends across the width of the cabinet between the front and rear walls thereof, and the side walls 43 and the bottom wall 44 extend to the rear wall 25 to seal the opening 32 therein from the food storage compartment 23. The inner walls of the machinery compartment may be formed by a suitable metallic lining 45 and the outer wall formed by a metallic lining 46 preferably having a coating of vitreous enamel such as porcelain corresponding to the surface finish of the inner lining 21 of the food storage compartment.

It will be seen that the refrigerant condensing element and the refrigerant cooling element are arranged in substantially the same horizontal plane, the condensing element being arranged at the rear of the cabinet and the cooling element in alignment therewith adjacent the front of the cabinet. The cooling element may be mounted in the food compartment on the upright wall 42 by any suitable means and is provided with a freezing zone 48 in which may be inserted trays 49 for freezing substances such as water, and an air cooling zone 50 for cooling circulating air within the food storage compartment.

The condensing element comprises in general a motor-compressor unit 52 which may be of any suitable type preferably enclosed within a hermetically sealed casing, and a condenser 53. In the usual manner, gaseous refrigerant is withdrawn from the cooling element or evaporator 35 through conduit 54 by the compressor which compresses it and delivers the compressed gas through conduit 55 to the condenser 53 wherein it is liquefied. The liquid refrigerant is then delivered to the evaporator through conduits 56 and 57 after first passing through a high side float mechanism 58. Preferably the condenser is air cooled and for this purpose I have provided a fan 59 driven by a motor 60. This fan also circulates the air throughout the machinery compartment which air enters through the rear opening of the machinery compartment to remove heat generated therewithin.

In order that the refrigerating system heretofore described may be conveniently serviced, it is arranged to be slidably removable or insertable as a unit through the food compartment door. To accomplish this, I provide in this instance a plate 61 suitably secured to the top edges of the upright wall 42 and the side walls 43 of the machinery compartment. Offset portions are formed in the inner lining 22 of the side walls, adjacent the top of the cabinet, providing slideways 62 on which the plate 61 and the depending refrigerating system are slidably

mounted. It will be seen that the plate 61 forms the top wall of the machinery compartment 36 and extends from the upright wall 42 to the rear wall 25 of the cabinet. Gaskets 63 may be provided between the slideways 62 and the plate 61 to insure a complete seal between the machinery compartment and the food compartment, and as shown may be carried by the plate 61.

As heretofore mentioned, the machinery compartment is open at the rear and in communication with the outer atmosphere through the opening 32 in the rear wall 25 of the cabinet. To insure a complete seal between the food storage compartment 23 and the insulated machinery compartment 36, gaskets 64 of any suitable material such as rubber are provided. As shown these gaskets may be carried by the rear edges of the plate 61, the side walls 43 and the bottom walls 44. When the refrigerating system is mounted in operative position in the cabinet, the gaskets 64 provide a tight fit between the rear wall 25 and the food storage compartment.

To prevent marring the enamel finish of the cabinet when installing or removing the refrigerating system, the top edges of the front wall 42 of the machinery compartment 43 are provided with breaker strip 65 of some suitable non-heat conducting material such as rubber which also serves to prevent the conduction of heat from the machinery compartment to the food storage compartment. To remove the refrigerating system from the cabinet the finishing strips 22 about the top and sides of the door opening are first removed and the system may then be slid forward through the food compartment door opening. If desired, the offset portions 62 may be positioned slightly lower in the food storage compartment so as to permit the removal of the unitary structure without removing the top finishing strip 30.

In Figs. 5, 6, 7 and 8 of the drawings is shown another form of the invention in which the refrigerating system is also removable as a unit through the food compartment door. A refrigerator cabinet indicated in general at 70 is constructed of insulated walls including top wall 71, side walls 72, rear wall 73, bottom wall 74, and front wall 75 providing a food storage compartment 76. An outer metallic casing 77 is provided for enclosing the insulated walls. The front wall 75 is provided with an opening 78 leading to the food storage compartment and a movable closure member 79 is provided for closing the opening. The rear wall 73 is provided in this instance with two openings 80 and 81.

A unitary removable structure is arranged within the cabinet near the top thereof and comprises in general an insulated machinery compartment 82, a condensing element and a cooling element or evaporator 84. The insulated machinery compartment 82 is formed by a wall structure of some suitable insulating material such as cork board and comprises an upright wall 85 which extends across the width of the cabinet between the front and rear walls thereof and a bottom wall 86 which extends to the rear wall 73. As shown, the insulated machinery compartment 82 is open to the outer atmosphere through openings 80 and 81 in the rear wall of the cabinet. Mounted within the insulated machinery compartment is the condensing mechanism which includes in general a motor-compressor unit 87, a condenser 88 and a fan 89 for cooling the condenser, and for circulating the air within the compartment. It will be seen that in

this instance the motor-compressor unit, condenser and fan are arranged in a different relation than those shown in Figs. 1, 2, 3 and 4 of the drawings, such that the fan may draw air in through the opening 80 and circulate it over the condenser and the motor-compressor unit and out the opening 81. The cooling element or evaporator 84 is suitably mounted on the upright wall 85 and comprises in this instance an upright portion 90 and a horizontal portion 91 which cooperate with the walls of the cabinet to form a freezing zone above and a cooling zone below. The cooling element or evaporator is operably connected with the condensing element by means of conduits 94 and 95 which extend through the upright wall 85 of the insulated machinery compartment. The inner walls of the insulated compartment 82 may be formed by a suitable metallic lining 96 and the outer walls are provided with a metallic lining 97 exposed to the interior of the cabinet and preferably having a coating of porcelain or other suitable vitreous enamel. The linings 96 and 97 also serve to provide an inner lining for the upper portion of the cabinet, and in this instance are adapted to be removable with the refrigerating system. The lower portion of the cabinet is provided with a lining member 69 which may be fixed in the cabinet. The edges forming the door opening 78 are provided with finishing strips 98 secured to the walls of the cabinet by some suitable means such as screws and serve to cover the terminating edges of the outer casing 70 and the inner linings 96 and 97 and the food compartment lining 69. The lining members 96 and 97 are provided with inturned flanges 99 which extend along the sides and rear walls of the cabinet and the lining member 69 is also provided with similar inturned flanges 100 adjacent the flanges 99. Gaskets 101 are provided between the flanges 99 and 100 to insure a complete seal between the insulated machinery compartment and the food storage compartment and may be carried by and secured to the flanges 100. Thus the refrigerating system is slidably supported on the flanges 99 and 100 and may be removed through the door opening 78 by first removing the finishing strips 98 and sliding the entire system including the linings 96 and 97 through the opening thereof. Although only a preferred form of the invention has been illustrated, and that form described in detail, it will be apparent to those skilled in the art that various modifications may be made therein without departing from the spirit of the invention or from the scope of the appended claims.

What I claim as my invention is:

1. Refrigerating apparatus comprising in combination, a cabinet having a compartment, an upright insulated wall extending across at least a portion of the width of said compartment and between the front and rear of the cabinet, a refrigerant condensing element on one side of said upright wall and a plate type refrigerant cooling element on the other side thereof and cooperating therewith and with other walls of the cabinet for dividing said compartment into a freezing zone and a cooling zone.

2. Refrigerating apparatus comprising in combination a cabinet having a compartment, an insulated compartment within the first named compartment and including an upright wall extending at least substantially across the width of said first named compartment and between the front and rear of the cabinet, a refrigerant condensing

element within said insulated compartment and a plate type refrigerant cooling element cooperating with said upright wall and other walls of the first named compartment for dividing said first named compartment into a freezing zone 5 and a cooling zone.

3. Refrigerating apparatus comprising in combination a cabinet having a compartment, an insulated compartment within the first named compartment and including an upright wall extending at least substantially across the width of said first named compartment and between the front and rear of the cabinet, a refrigerant condensing element within said insulated compartment and an L shaped plate type refrigerant cooling element having an upright portion adjacent the upright insulated wall and a horizontal portion extending toward the front of the cabinet, said cooling element cooperating with walls of the cabinet for dividing the first named compartment into a freezing zone and a cooling zone.

4. Refrigerating apparatus comprising in combination a cabinet having inner lining material, a guideway formed by said lining material, slideable means cooperating with said guideway, and a unitary structure including refrigerant condensing and cooling elements operatively associated with one another with the cooling element arranged in advance of the condensing element and carried by said slideable means adjacent the upper interior of the cabinet.

5. Refrigerating apparatus comprising, in combination, a cabinet having an upright wall, a refrigerant evaporating element including a vertical portion carried by said upright wall, and a horizontal portion associated with the lower part of said vertical portion and extending forwardly to the front part of said cabinet, said horizontal portion cooperating with walls of the cabinet for dividing the interior of said cabinet into a freezing compartment and a food storage compartment, said cabinet having an opening in a wall thereof through which access to said compartment may be had, and closure means for said opening.

6. Refrigerating apparatus comprising, in combination, a cabinet, an integral inner metallic lining member disposed in said cabinet and being arranged to form the walls of a food storage compartment, said lining member being bent to form guideways adjacent the top wall of said compartment and being provided with an opening in the front part and an opening in the upper rear part, a unitary refrigerating apparatus slidably supported by said guideways adjacent the top wall of said compartment, said unitary apparatus including an insulated wall structure having an opening registering with the opening in the rear part of said lining member, a refrigerant condensing element disposed on one side of said insulated wall structure, a refrigerant cooling element disposed on the opposite side of said wall structure in advance of the condensing element and in said food storage compartment, said unitary apparatus being arranged to be slid from said compartment through the opening in the front part of the lining member, and closure means for said latter opening.

7. Refrigerating apparatus comprising, in combination, a cabinet having an upright wall, a refrigerant evaporating element including a horizontally disposed portion associated with said upright wall and extending forwardly toward the front part of the cabinet, said horizontally disposed portion cooperating with walls 75

- of the cabinet for dividing the interior of the cabinet into a freezing compartment and a food storage compartment, said cabinet having opening means in a wall thereof through which access 5 to said compartments may be had, and closure means for said opening means.
8. Refrigerating apparatus comprising, in combination, a cabinet having an upright wall, a refrigerant evaporating element including a 10 vertical portion associated with said upright wall, and a horizontal portion associated with said vertical portion and extending forwardly toward the front part of said cabinet, said horizontal portion cooperating with walls of the 15 cabinet for dividing the interior of said cabinet into a freezing compartment and a food storage compartment, said cabinet having opening means in a wall thereof through which access to said compartments may be had, and closure means 20 for said opening means.
9. Refrigerating apparatus comprising in combination, a heat insulating cabinet, an inner lining of sheet metal in said cabinet and having guideways formed therein, and a refrigerating 25 unit including a motor compressor condenser evaporator unit slidably disposed on said guideways, said cabinet having an opening associated with said motor compressor condenser.
10. Refrigerating apparatus comprising, in 30 combination, a cabinet having an opening in an

upright wall thereof, a wall having an opening, movable closure means for said opening, a refrigerant condensing element located on one side of said closure means, a refrigerant evaporator comprising an imperforated wall structure located on the opposite side of said closure means and being positioned in said cabinet in such a manner as to cooperate with inner walls thereof to divide the interior of the cabinet into a food storage compartment and a low temperature compartment, said condensing element, movable closure means and evaporator being removable bodily as a unit from said cabinet through said opening in said upright wall thereof. 5 10 15

11. In a refrigerator, the combination of heat insulating walls defining a heat insulated enclosure, a removable portion included in one of said heat insulating walls, a refrigerant evaporator comprising a flat partition like member, 20 means on said removable portion for supporting said evaporator cooperatively adjacent said heat insulating walls to divide the enclosed space into compartments, a refrigerant compressor, conduit means for operatively interconnecting the 25 compressor and evaporator, and means for securing said compressor to the opposite side of said removable wall portion.

LAWRENCE A. PHILIPP. 30
